UNITED STATES PATENT OFFICE.

JAMES H. MANN, JR., OF MONTEAGLE, TENNESSEE, ASSIGNEE TO SOUTHWESTERN SALES CORPORATION, OF NEW YORK, N. Y., A CORPORATION OF DELAWARE.

SPURIOUS-COIN SEGREGATOR.

Application filed February 27, 1924. Serial No. 695,484.

This invention relates to a device for detecting and segregating spurious coins and relates more particularly to means for detecting and arresting perforated inserts.

5 It is the object of my invention to produce a vending machine of the character described which is provided with a coin channel in which is located means for testing the diameter of an insert together with means for 10 arresting an insert that does not respond to the predetermined requirements of measurement, means for detecting and arresting an insert of magnetic metal, means for detecting and arresting an insert of other than 15 predetermined weight, and more particularly means for detecting and arresting a perforated insert, all of which means are associated with means for releasing spurious inserts and by-passing them away from the 20 channel which leads to the operating mechanism of the device.

In the accompanying drawings:

Figures 1^a and 1^b illustrate front and back views of the fixed wall of the chute as 25 contained in the present embodiment and showing the weight detector,

Figure 2 gives a front view of the chute closing plate showing the magnetic detector device together with the pawl mechanism 30 for spearing perforated tokens or the like,

Figure 3 corresponds to an edge view of the slide,

Figure 4 gives a back view of the slide for the chute opening and closing plate,

35 Figures 5^a and 5^b illustrate an inside and outside view of the back plate showing the lugs for automatically disengaging magnetic material from the detecting magnet,

Figure 6^a gives a view with back cover removed of the casing enclosing the spurious coin or token segregator mechanism, and Figure 6^b gives a perspective view of the casing,

45 Figure 7 illustrates in perspective a view of the collecting chamber partition for the standards passing through the segregating chute,

Figure 8 illustrates a spacer employed to position the detecting and segregating 50 mechanism within the casing, and

Figure 9 is a view of a partial assembly of the internal detecting and segregating mechanism,

Figure 9^a is a front view of the fixed wall

of the chute with the discharger or chute-closing plate mounted thereon.

Figure 10 illustrates a rear view of the assembled structure,

Figure 11 corresponds to a detail view of the actuator bolt,

Figure 12 is a side view of my frame and movable plate in normal closed position; and

Figure 13 is a similar view showing the parts spread apart.

Within a casing 1, preferably vertically arranged and having slots 2 for the reception of a standard coin or token there is inserted a detecting frame 3 having slot chutes 4-4

and with a central passage 5 leading to a chute 6. Within the channels 4-4 there are 70 provided diameter detecting means comprising a deflecting wedge 8 adapted to engage a spurious specimen that is thinner than standard so that it will automatically slip out of the chute when the deflecting wedge 75

engages the tilted specimen as the top half of the latter loses touch with the top groove guides 9 of the channel 4. Thin inserts fail to lodge against the wedge 8 when riding on the bevelled edge 9' of the plate 10; are deflected away from the passage 5 and are bypassed to the delivery gate 39. Standard specimens (such as nickel for instance) would ordinarily be retained by virtue of a chute discharging plate 10 co-acting to retain 85

them firstly in the channel or chute 4 by virtue of the upper lips 9, and the lower lips 9' of the plate 10 co-acting to guide the tokens in their travel along the central passage 5 and therefrom into the chute 6. Nevertheless, with coins that are of sufficiently full diameter it is sometimes found that they tend to stick into the slots in which they are placed. In order to avoid such a tendency 90

teaser slots 11^a are provided, such that teaser fins 12-12 may be inserted and with an upward movement of the latter the fins engage the lower edge of the specimen dislodge same from the slot 4 and impel it into a spurious coin return delivery slot to be described later. The fins 12 are carried by a separating embracing slide 13 and with wedge shaped turned-up portions 14-14' fitting over the edges 15 of the frame 3.

This is more clearly indicated in Fig. 9 105 showing the internal assembly of the device. It will be noted that a lug 16 integral with the slide is arranged to pass through a slot

17 of an actuator bar 18. The latter is better visible from the front view of the frame 3. The slide 13 covers the back of the frame 3 and imparts an oscillating movement to 5 the discharger plate 10 by the engagement of the upper inclined edge portion 19' with the projections 19—19 on the plate 10. This gives to the latter an outward motion away from the frame 3 thereby separating the

10 walls of the central passage or chute 5.

The open position of the frame 3 and plate 10 is illustrated in Figure 12. These parts are returned to closed or normal position by the tension of the spring 20. In such action, 15 the cam face of the wedge shaped turned up portion 14' rides over the top of the projections 19—19 on the plate 10 to force the same toward the frame 3 and into the collapsed position shown in Figure 13. Thus 20 as the actuator bar 18 is moved upwardly, it not only causes an expansion of the walls constituting the chute 5 by moving the discharger plate 10 away from the frame 3 but at the same time it also causes teaser fins 12 25 to dislodge the full sized specimens in the branch chutes 4—4. With the specimen being standard ample time is given for it to traverse the central passage and pass into the segregating chute 6 before the oscillating 30 action is much advanced. Furthermore to facilitate a quick dislodgment the plate 10 carries the guide lips 9' lying over the bevel lower portion of the chute 4. Oftentimes a 35 slug may have the right diameter but not the proper weight. There is, therefore, arranged along the central passage 5 a weighing tripper 21 working in conjunction with a curved passage 22, such that provided the action of the discharger is not brought 40 about, the underweight specimen will lodge therein, until with the wall separation of the central chute 5, the spurious member will fall away from and not enter the standard chute 6. Often times the needed weight and 45 diameter is brought about by using a perforated slug of denser material than the standard. In this case a spearing pawl 23 is provided mounted in such a manner upon the discharger plate 10 that as the 50 finger of the pawl, in feeling along the specimen, engages with the centrally located perforation, it is drawn inwardly and only when the plate functions is the pawl enabled to 55 sufficiently revolve back to normal by contacting with the mounting plate to enable the spurious member to be disengaged therefrom and discharged outside of the standard chute 6.

In addition thereto, besides using the 60 heavier metal lead for spurious tokens, magnetic material such as iron can be used as in the form of slugs or discs. To avoid this possibility a magnet 24 is mounted on the discharger plate in such wise, by virtue of 65 a deflecting boss 25 in the wall of the cen-

tral chute 5, and opposite the magnet 24, all magnetic materials are brought sufficiently close so as to be in attracting range of such magnet. A second function of the boss 25 is to deliberately hold back a second magnetic specimen, should the breather plate not operate to discharge the first magnetic substitute token or slug, which latter operation will now be explained.

It will be seen that a mounting or back plate 26 forms an enclosing wall of the casing 1, such back plate or wall carries lugs 27, the projections of which are capable of passing through and between the legs 28 of the magnet as the plate carrying the magnet approaches the back plate and moves away from the frame 3. The discharge of the magnetic material is thereby suitably effected. If after passing the various detecting devices the specimen satisfies all required 75 conditions, the standard will pass into the chute 6, before the oscillating plate can be brought to function. Preferably, in order to bring the actuator rod into normal position an actuator spring 20 is connected 80 at one end to a lug 30 on the frame 3, and the other end is attached to the lug 16 of the slider after the lug has passed through the slot 17 of the actuator rod 18.

A spacer 30' is employed for properly positioning the frame 3 and its cooperating parts within the casing 1. At the same time note should be taken of the fact that ordinarily a partition 31 is placed at the bottom portion 32 of the casing 1 in order that a segregating receptacle 33 may be formed as a continuation of the chute 6. To one side of the receptacle is a fin or lip 34 perforated for the reception of an actuator bolt 35, the end of which is grooved as at 36 for engagement with a slot 37 in the upset portion 38 of the actuator bar 18. The partition 31 moreover has a gate 39 for delivering the spurious specimens passed through the machine. Preferably also a delivery slot 40 is also provided at the side of the casing through which the standard specimens can be obtained from the receptacle 33.

In operation, therefore, on placing various slugs, coins, tokens, etc., into the slots 2 of the casing, the diameter detection automatically follows by virtue of the distance separating the lips 9, 9'. Should the diameter prove insufficient the spurious specimen will tilt toward the breather plate and by engaging the bevel surfaces of the spear 8 fall outside of the chute track 4 and be deposited above the bottom 32 of the casing 1 to appear at the gate opening 39 ready to be taken away. Should the diameter be slightly too full such as to tend to bind within the guiding limitations 9, 9' the specimen will remain lodged until the actuator bolt 35 is operated. On pressing the latter upwardly the teaser fingers 12 rise through the 100 105 110 115 120 125 130

teaser slots of the chute 4 and dislodge the same. As the slide 13 carrying the teaser fins moves upwardly the lower lips 9' integral with the plate 10 are moved away permitting the slightly oversized slug or token to fall between the plate 10 and the frame 3 to the gate 39. Such oscillating action of the main chute 5 is brought about by virtue of the spacing wedge-shaped portions 14 engaging with the breather plate tending to move the latter outwardly by virtue of the projections 20 engaging freely in the slots 20' of the frame. The slide is mechanically united with the actuator bar 18 by virtue of the lug 16 of the slide engaging with a suitable slot 17 of the bar. The return action of the bar is obtained by means of the actuator spring 30 tending to pull the slide and bar toward the bottom of the casing.

20 The specimen insert having successfully passed the diameter detecting device is then subjected to the action of a magnetic detector mounted on the plate. The insert, however, is led through by means of a boss or the like 25, whose function it is not only to throw the specimen into the attracting range of the magnet, but should the insert have proved to be magnetic, the boss, coupled with the magnetic specimen, will choke 25 the channel or chute 5 toward the passage of any additional magnetic slugs until the actuator bar and breather plate have been actuated to by-pass the spurious insert. To effect the latter step the back plate is provided with projections or lugs 27 that pass through between the legs of the magnet as the breather plate is actuated by the bolt. The magnetized specimen becomes detached and falls outside of the track 4 as before described.

40 Having passed the previous tests, an insert encounters the pivoted pawl 23 which arrests any perforated specimens by the finger end of the pawl hooking into the perforation. Such arrested specimen is detached by the functioning of the pivoted plate 10 as previously described, when the

50 weighted lower end of the pawl rocks the pawl upon its pivot as the plate is spread away from the frame 3. The insert is thereupon by-passed toward the discharge gate 39. On the other hand the insert having all the other needed qualifications may still be short weighted, in which case the weight detecting tripper 21 is encountered before 55 the bend 22 of the chute 5 is passed. Such spurious specimen will similarly remain lodged until the bar 18 is operated, in which case by virtue of the bevel given to the wall of the bend 22 it is sufficient to pass the 60 specimen toward the discharge gate 39. At the same time, with the above upward movement of the slide and actuator, it will be seen that the tripper 21 is automatically operated by virtue of an offset 40' on the 65 slide engaging with a similar offset 41 on the weighted tripper arm. This type of movement is necessary when an irregularly shaped specimen becomes lodged in the channel 5 between the edge of the tripper 70 21 and the curved wall of the channel 22. Thus the chute channel construction 4, 5, 22 and 6 is always cleared of obstructions whenever the actuator bar is operated. The specimens satisfying all conditions naturally pass 75 into the chute 6 without the need of the bar being operated. Nevertheless, if desired such bar may be operated after each insert is made to the feeding chute.

Having disclosed the nature of my invention what I claim is:

In combination with a coin chute, a movable plate forming one wall thereof, means carried on said plate for arresting a perforated insert, a sliding wedge shaped member 85 contacting with said plate to move the same to release the arrested insert and by-pass it from said chute, and means to restore said wedge-shaped member, movable plate and arresting means to normal position. 90

In testimony whereof I have hereunto set my hand.

JAMES H. MANN, JR.
